UNITED STATES PATENT OFFICE.

ALEXANDER A. SCOTT, OF KNOXVILLE, TENNESSEE, ASSIGNOR TO BALTIMORE TRUST COMPANY, TRUSTEE.

PARTITION CAR FOR HANDLING ARTICLES.

Application filed March 15, 1921. Serial No. 452,507.

To all whom it may concern:

Be it known that I, ALEXANDER A. SCOTT, a citizen of the United States, and a resident of Knoxville, in the county of Knox and 5 State of Tennessee, have invented an Improvement in Partition Cars for Handling Articles, of which the following description, in connection with the accompanying drawings, is a specification, like numerals on the 10 drawings representing like parts.

In the manufacture of soft mud or moulded brick, it is necessary to utilize pallets on which a plurality of brick will be handled and in my present invention I have 15 devised means to assemble a plurality of such brick directly from the pallets onto a combined conveying and unit stacking apparatus. Broadly considered, my present invention has for its object the provision of 20 means which will enable a unit formation of moulded brick to be assembled thereon, directly from the pallets on which the moulded brick has been made or dumped, and preferably after they have been through the 25 drier, simultaneously stacking the brick in unit formation and removing them from the pallet. It is also an important feature of the present invention to enable moulded brick to be built into unit form, whereby the brick 30 can be subsequently handled by mechanical setters, lifters, or other devices, and I have also applied such a unit building device to a vehicle, truck or the like so that after the pallets are thus unloaded and the unit built, 35 the same can be moved or transported to the hacking machine adjacent a kiln, and either transferred into hacked units or built directly into the kiln while unloading the same from the unit stack thus constructed. 40 Further important features consist in the provision of automatic means which will space the brick for hacking or kiln setting, means permitting removal of the brick and displacement of the spacing means or partitions by a cooperative carrier, together 45 with other advantages and features.

In carrying out my invention I provide a suitable support such as the platform of a truck, vehicle or car, although the same may 50 be utilized simply as a pallet unloading and unit building station if desired. With the truck platform of suitable height for the convenient unloading of the pallets, I also provide a plurality of spaced partitions 55 formed as sliding members, and preferably

with counterbalanced weights, so that these sliding partitions can be easily raised and lowered and will be maintained wherever thus positioned, vertically. The operators will position the loaded pallets with one end 60 on the platform, raising the other end and thus sliding the brick off the pallet onto the platform, and a further raising of the pallet will enable the brick therefrom to be stacked in vertical position. Thus the pallet is readily removed and the truck is 65 quickly filled, successive pallets being unloaded thereon as quickly as delivered, from the conveyor or other means to the truck. In order to space the stacks of brick thus unloaded onto the truck, I provide a plurality 70 of vertically movable partitions, preferably so arranged that when a column of brick two high has been piled widthwise of the truck, a partition may be raised, which will separate and space the first double columns of brick and constitute a backing for the next succeeding pallets. After two more rows or 75 columns of brick have been positioned vertically against the partition, another partition is raised and so on until the entire truck is loaded. The truck can then be transported to adjacent the kiln and I provide a cooperating carrier for the unloading of the brick thus transported in vertically 80 stacked formation. In this carrier I provided means cooperating with the partitions and spaced equally therewith, so that the lowering of the carrier will act to depress the partitions as far as one or more of the 85 topmost courses of brick, thereby releasing these courses of brick from the partitions and simultaneously permitting the engagement of the lifting devices of the carrier. Thereupon the top brick so released may be 90 clamped or otherwise engaged and the row or rows so released from the partitions of the truck and clamped by the carrier, can be readily removed and built into the kiln, or into other unit stack formation for subsequent handling. As the partitions are 95 balanced and therefore maintain any vertical position to which they may be placed, the removal of one layer or layers of brick automatically prepares the truck and the partitions for the similar removal of a succeeding layer or layers until the lowermost or bottom courses have been reached and removed.

My method of thus handling brick which 110

have been moulded or positioned onto a pallet, resulting in providing a unit building and simultaneously pallet unloading operation, is, I believe, a distinct novelty in this art, and I wish to claim the same herein broadly.

Further features of the invention, novel combinations of parts and details will be hereinafter more fully pointed out and 10 claimed.

Referring to the drawings, illustrating a preferred embodiment of the invention,

Fig. 1 is a side view illustrating the process of building a unit from pallets on my 15 partition car;

Fig. 2 is a side view illustrating the method of removal of layers or courses of brick from the car; and

Fig. 3 is an end view.

20 It will be appreciated that my invention is not limited to the type of conveying device herein illustrated, but can be advantageously employed as a loading station, or as an automobile truck with a capacity of one or more units. Such a completed truck would be useful for handling and transporting burned brick maintaining the brick, tile or articles thus carried, in unit formation to facilitate unloading in orderly layers or groups. My 25 invention, however, is primarily for use in handling green brick during the process of manufacturing and for use in building a unit of such green brick directly from a pallet, simultaneously unloading the pallet, forming 30 the unit and also loading the brick on a car or movable device which can transport the same to any desired point for subsequent handling by mechanical conveyors, thus eliminating hand operations and being an 35 important link in automatic systems of brick manufacture.

A partition car of simple form is here illustrated, wherein a platform 1 is supported upon a suitable axle 2 and pair of wheels 3, 45 3, for moving and transporting. Preferably the platform 1 is of a considerable height above the ground, and may be positioned above the axles to allow for the lowering or housing of the partitions 5 below the 50 horizontal plane of the top of the platform 1. For this purpose the platform 1 must be sufficiently above the ground to afford space for the housing of these partitions equal to or somewhat greater than the height of the partitions above the platform 1 when in use, 55 and therefore the space below the platform must be approximately the same as the height of the unit to be built on the carrier. This platform 1 is slotted at a plurality of 60 points 6, 6, 6, crosswise of the same and with these slots properly spaced to receive sliding portions 7 of the partitions which latter are designated generally at 5. These partitions may be formed in any desired way, 65 but as illustrated in Fig. 3 are preferably a

plurality of slats or members 7 united at the top by a crossbar as designated by the reference character 5 which is utilized as a reference to the entire partition, and at the bottom by crossbars 8.

70 Each of these partitions is substantially like the other in construction and operation and therefore the description of one will be sufficient for all, it being understood that as many of these partitions are arranged in a car and through the platform 1 as is desired for the capacity of the car and for the unit or units to be built thereon.

75 Each partition 5 is not only arranged to slide vertically through its slot 6, but is also preferably counterbalanced so that the partition can be easily and quickly raised or lowered to any height within the limit of its vertical movement and maintained there without locks, difficulty, or other action. For 80 this purpose I provide a counterweight 10 attached to a pair of ropes, wires or chains 11, each running over sheaves 12 pivoted in appropriate recesses in the platform 1 as clearly illustrated in Figs. 2 and 3. The counterweight 10 is of sufficient weight to balance the partition 5 which is carried by the opposite end of the rope 11, the friction of the rope and pulleys, as well as of the 85 sliding parts 7, in the slot 6 through the platform being sufficient to maintain the partitions 5 and counterweights 10 wherever moved.

90 In order to steady the apparatus I provide a pair of depending guides 14, 14, for 100 each counter weight 10, these guides being located under the platform 1 and secured thereto, these guides also serving to define a space in which the partitions 5 are housed when in lowered position.

95 I also prefer to apply fixed guides or 105 guards 15 at one end, side or appropriate point on the apparatus, with a beveled face 16 as a fixed guide for the positioning of the overhead carrier or mechanical lifter in unloading the brick from the apparatus, as 110 will be described.

115 It will be understood that my partition car, while primarily intended for use in building a unit of brick directly from pallets, can also be employed for building a unit by hand, or conveyors or otherwise. As herein illustrated, I have shown the same as for use in connection with the manufacture of moulded brick, wherein the pallet 120 is employed, and consequently will describe the building of the unit thereon by unloading pallets. It is customary for these pallets 20 to have a plurality of brick, from five to eight, thereon, as is well known, an average number being six, as illustrated in the row of brick 21 on the pallet 20 in Fig. 1. I have, therefore, illustrated the present apparatus as having partitions 5 of sufficient 125 length and capable of ample vertical move- 130

ment to take care of the building of a unit of six brick high. The operator, when ready to build a unit on the apparatus, raises the first partition 5, which will stay where 5 positioned, through the lowering of the counterweight 10 and the frictional action of the slats or members 7 through the slots in the platform 1. The operator simply lowers one end of the pallet 20 adjacent the 10 partition, raises the other and thus slides the entire series of brick downwardly, resting on the platform, and simultaneously raising the pallet 20 to vertical position, stacks the brick against the partition. This 15 action starts the building of the unit, unloads the pallet, upends the larger brick into a vertical column and partially positions the same for unloading.

It will be understood that the partitions 20 5 may be provided in sufficient number and spacing for any group or number of brick in a column, that herein shown being suitable for building a unit of brick with two in each column widthwise thereof, and of 25 sufficient length of the column of brick or widthwise of the apparatus for the size of unit desired. The operator therefore builds the first column of brick against the partition 5 by unloading successive pallets 20 30 and thereupon builds a second column of brick by unloading successive pallets directly against the first column, until the same is completed entirely across the width of the platform 1. As herein illustrated, the 35 platform is built for a unit four brick wide and twelve long, see Figs. 2 and 3. When the two brick column is completed across the apparatus, the operator then raises the next partition 5, thus spacing and maintaining 40 the column thus built and constituting a backing for the second column and so on until the entire unit is constructed on the apparatus by the unloading of successive pallets 20 and the standing of brick on end 45 during this unloading, thus building the unit, and also having the unit built on a platform which can be moved. With the unit stack of brick thus built, and all the partitions 5 raised to vertical limit, the car 50 or apparatus can be transported to a convenient point in the brick yard or for unloading, and thereupon the brick can be unloaded by a mechanical lifter, setter or carrier. Any suitable type of lifter can be 55 employed, the apparatus herein shown being merely for illustrative purposes, and being designated generally at 25. This carrier 25 is of appropriate dimensions to engage the entire topmost course of brick, i. e., four 60 wide and twelve long, and for this purpose has a framework 26 adapted to extend over the topmost layer or course 27 of the brick. As I may desire to lift a plurality of layers, I have herein shown the carrier 25 with a 65 plurality of lifting or clamping fingers 30

of sufficient extent to engage the two topmost rows of brick, 27 and 28, simultaneously, to lift and remove the same from the car. The carrier has formed thereon a plurality of sets of fingers 30 depending from the framework and mounted for lateral movement on rods 32 and 33. The simple form of carrier is herein illustrated, wherein the outermost fingers 30 are mounted rigidly on the rods 32 which latter are actuated by springs 35 to effect an inward clamping action, serving to force all the brick in the rows 27 and 28 and in the columns of each inwardly, sliding the inner fingers 30 on their rods 33 and thus effecting a clamping action throughout the mass and layers of the rows of brick thus engaged. The operation of this action is necessarily delayed until the partitions 5 are removed. After said removal the levers 36 may be actuated to 85 effect the release of the springs 35, which latter may be furthermore actuated by the lifting action of the rod 38, lifting the entire apparatus, and exerting a sufficient tension on the springs 35, rods 32, and outermost fingers 30, through bell cranks 39, 39, to lift the entire lot of bricks.

In order to position the carrier and the fingers 30 about the topmost layers to be removed, the carrier is simply lowered into position, the outermost fingers 30 adjacent the guide 15 striking against the beveled surface 16 and thus automatically guiding the entire carrier into position so that the several fingers 30 will be in alinement with the several partitions 5 on the car, each finger being normally spaced appropriately for this alining action. Thereupon the further lowering of the carrier 25 by its weight depresses the counterbalanced partitions 5, 100 permitting the partitions to be depressed and lowered as far as the fingers of the carrier extend. This position is illustrated in Fig. 2, so that the carrier when in lowered position has automatically removed the 105 partitions from their separating engagement with the topmost rows 27 and 28, thus permitting these rows to be moved or slid inwardly during the clamping action of the carrier, as above explained, and consequently to be lifted freely and removed from the apparatus. This unloading operation is repeated until the entire unit of brick has been removed, and thereupon the partitions 5 are in their lowermost or housed position, and the entire car is ready to receive a successive unit of brick to be built thereon.

My invention thus has a capacity for carrying out the novel process of simultaneously building a unit of brick for subsequent handling by mechanical carriers, setters, etc., as a step in the process of the automatic manufacture of brick, which building is performed by the action of unloading brick from the pallets on which the 110 115 120 125 130

brick has been transported or made. Furthermore, this action of building the unit and of unloading the pallets, is effected by the further action of placing the brick in 5 a vertical column and on edge. This feature is most important, because moulded brick on pallets are laid flat, whereas brick when piled in a kiln are set on edge. Therefore this "edging" action is an essential step 10 in the handling of brick during their process of manufacture and has heretofore been performed mainly, if not entirely, by hand. It will, therefore, be seen that this carrier contemplates the simultaneous and practically automatic action of the triple steps 15 consisting in unloading the brick from pallets, edging up the brick for hacking, and building the unit. These novel features are intended to be claimed broadly herein.

20 My invention is further described and defined in the form of claims as follows:

1. A movable truck having a platform, a plurality of vertically movable partitions carried by said platform, and appropriately 25 spaced for the formation thereon of a unit stack of brick, in predetermined spaced relation, means to move the partitions vertically at will during loading, and means for lowering the partitions during unloading.
- 30 2. A movable truck having a platform, a plurality of vertically movable partitions carried by said platform, and appropriately 35 spaced for the formation thereon of a unit stack of brick, in predetermined spaced relation, and means for lowering the partitions operable by the positioning of an unloading carrier on the truck.
- 40 3. A movable truck having a platform, a plurality of vertically movable partitions carried by said platform, and appropriately spaced for the formation thereon of a unit

stack of brick, in predetermined spaced relation, means for lowering the partitions by the lowering of an unloading carrier and means to guide the carrier into position for 45 the lowering of the partitions.

4. A truck of the kind described, adapted for use in the handling and transporting of brick and suitable for the building of a unit stack of brick thereon by the unloading of 50 pallets, comprising a platform, a plurality of slots through said platform, a plurality of partitions having portions adapted to slide through the slots in said platform, and counterbalancing means, whereby the partitions may be retained in any vertical position desired.

5. Apparatus of the kind described, consisting in a movable truck having a plurality of vertically movable partitions, properly 60 spaced for predetermined columns of brick, to be built thereon, means permitting the moving of successive partitions into position during the progress of the building of the unit, and means to retain the partitions in 65 uppermost brick engaging position during the transporting of the unit.

6. Apparatus of the kind described, consisting in a movable truck having a plurality of vertically movable partitions, properly 70 spaced for predetermined columns of brick, to be built thereon, means permitting the moving of successive partitions into position during the progress of the building of the unit, and means to retain the partitions 75 in uppermost brick engaging position during the transporting of the unit, said partitions being removed during the unloading of courses of brick from the unit.

In testimony whereof, I have signed my 80 name to this specification.

ALEXANDER A. SCOTT.
